UNITED STATES PATENT OFFICE

HAROLD C. EDDY, OF LOS ANGELES, CALIFORNIA, ASSIGNOR TO PETROLEUM RECTIFYING COMPANY OF CALIFORNIA, OF LOS ANGELES, CALIFORNIA, A CORPORATION OF CALIFORNIA

METHOD OF AND APPARATUS FOR DEHYDRATING PETROLEUM OIL

Application filed August 4, 1926, Serial No. 126,972. Renewed September 1, 1928.

My invention relates to a novel form of electrical dehydrator adapted for use in de-emulsifying petroleum oil.

Petroleum oil as it is taken from a well carries particles of trapped water which can be removed therefrom only by a special process. Electrical dehydrators are used extensively for the purpose of de-emulsifying the petroleum oil. A common form of electrical dehydrator consists of a tank in which a pair of electrodes of different polarity is placed. These electrodes are included in an electrical circuit so that a high potential electric field may be set up in the space between them. The emulsified oil is passed through the electric field and the small particles of water are caused to coalesce by the action of the electric field, forming globules of water which are of sufficient size to separate from the oil by gravity.

I have found that the de-emulsifying of the oil may be facilitated by mixing the emulsified oil with the oil which has been previously treated, and then passing this mixture through the electric field.

It is an object of this invention to provide an electrical dehydrator in which the emulsified oil is mixed with a treated or de-emulsified oil just before it is passed through the electric field of the dehydrator.

Other objects and advantages of the invention will be made evident hereinafter.

Referring to the drawing in which I illustrate the invention,

Fig. 1 is a vertical section through a dehydrator in which the features of my invention are incorporated.

Fig. 2 is a section taken on the line 2-2 of Fig. 1.

Fig. 3 is a fragmentary section of the upper end of Fig. 1, being taken at right angles thereto.

Figs. 4 and 5 are enlarged fragmentary sections showing a valve structure of the invention.

The form of the invention shown in the drawing consists of a tank 11 providing a de-emulsifying chamber 12. A frusto-conical grounded electrode 13 is secured near the lower end of the chamber 12 by suitable

straps 14, there being an annular space 15 between the periphery of the grounded electrode 13 and the side walls of the tank 11. Extending downward from the central part of the grounded electrode 13 is a tube 17, 55 the lower end of which is constricted as indicated at 18. At the upper end of the tube 17 is a plurality of openings 19. Emulsion or emulsified oil is introduced into the lower end of the chamber 11 by means of an emulsion inlet pipe 20. The emulsion inlet pipe 20 is provided with an upwardly extending leg 21 which extends through an opening 22 in the lower part of the tube 17 to the interior thereof.

Supported above the grounded electrode 13 is a live electrode 25. The live electrode 25 has a frusto-conical member 26 which, as illustrated in Fig. 1, is of sharper taper than the grounded electrode 13. Secured to the frusto-conical member 26 is a plurality of concentric rings 27. There is a treating space 29 provided between the electrodes 25 and 13. It should be noted that near the central part of the treating space 29 the distance between the electrodes 26 and 13 is much greater than the distance between these electrodes at the extremities of the treating space 29.

The live electrode 25 is provided with straps 30 which are attached to the frusto-conical member 26, these straps supporting an upper shaft 31. The upper shaft 31 is attached to an insulator 33 which is supported at the lower end of a hanger rod 35. The hanger rod extends upward through a bearing 36 and the upper end thereof is attached to a link 37, which is attached to a crank pin 38 of a crank 39. The crank 39 has a shaft 40 which is rotatably supported by a bearing 41 90 attached to the upper part of the tank 11.

Secured in the top of the tank 11 is an insulator bushing 42 to which a wire 43 is attached. The wire 43 is also attached to the live electrode 25 by means of which electrical energy is supplied thereto.

Referring in particular to Figs. 2, 4 and 5, the central part of the frusto-conical member 26 has a short cylindrical portion 46, at the upper end of which is formed a radially ex-

- tending annular flange 47 and a cross bar 48. A hinge-bar 50 is extended across the short cylinder 46 immediately below the cross bar 48 and valve plates 51 are pivoted thereto, these valve plates being for the purpose of closing openings 52. Any suitable form of spring, such as indicated by the numeral 54, may be provided for resiliently retaining the valve plates 51 in the position shown in Fig. 4. The valve plates 51, however, are capable of being moved into the position indicated in Fig. 5 so that the openings 52 are unobstructed.

These resiliently mounted valve plates 51 thus comprise a one-way valve means which admits dry treated oil to the treating space, but prevents any reverse flow.

The operation of the invention is substantially as follows:

- 20 The emulsion which consists of oil and water is introduced into the tank 11 by the pipe 20. This emulsion passes into the tube 17, flowing upward into the treating space 29. The grounded and live electrodes 13 and 25, 25 according to standard dehydrator practice, are included in a high potential electrical circuit, the tank being grounded and the bushing 42 having a conductor connected thereto so that a high potential electric field is set 30 up in the treating space 29. The emulsion passes outward through the treating space 29 and the particles of trapped water are coalesced into globules of water which have sufficient weight to separate from the 35 emulsion by gravity. As the emulsion is treated, it is gradually freed of its water content, the water content falling to the bottom of the chamber 11, forming a body as indicated by the numeral 55. The water 40 may be withdrawn from the chamber 11 by means of a water outlet pipe 56. The treated oil passes to the upper part of the chamber 12 and may be withdrawn therefrom through an outlet oil pipe 57. A small portion of the oil 45 which passes from the treating space 29 is carried through the annular opening 15 to the space above the body of water 55 but immediately below the grounded electrode 13.

When the emulsion passes into the central

- 50 part of the treating space 29, its water content is quite high and its dielectric properties are comparatively low as compared with the dielectric properties of the oil as it passes from the extremity of the treating space 29. 55 To compensate for this gradual increase in dielectric properties which occur as the emulsion passes outward, the electrodes 13 and 25 are so formed that the distance therebetween decreases as the outer portions of the treat- 60 ing space is reached.

When the dehydrator is in operation the crank 39 is operated so that the live electrode 25 is reciprocated from the position shown in full lines in Fig. 1 into the position 65 shown by dotted lines 58 of Fig. 1. It is well

known that the globules of water tend to form in short-circuiting chains between the live and grounded electrodes and that they reduce the efficiency of the dehydrator and increase its cost of operation. When the live 70 electrode 25 is reciprocated, as mentioned, these short-circuiting chains will be broken so that efficiency and economy will be maintained.

The primary purpose, however, of reciprocating the live electrode 25 is to operate the valve plates 51. During the up stroke of the live electrode 25 the valve plates 51 are moved from the position shown in Figs. 1 and 4 into the positions shown 80 in Fig. 5 and by dotted lines 59 in Fig. 1. When the live electrode is moved upward, the treating space 29 is enlarged and oil which has been de-emulsified or already treated in the treating space 29 is drawn through the 85 openings 52 into the central part of the treating space 29. The treated oil is at this point mixed with the emulsion passing upward through the tube 17, this mixture passing outward through the treating space 29. 90 The purpose of mixing treated oil with the emulsion in its passage through the treating space 29 is to maintain the fluid at a high dielectric strength so as to prevent the passage of disruptive discharges through the 95 body of oil or emulsion, thus allowing a high voltage to be maintained between the electrodes without appreciable current flow. During the down stroke of the live electrode 25 the treating space 29 is decreased and the 100 mixture being treated is forced outward therethrough. I have found that by mixing emulsion with a treated oil, very successful results may be obtained both from an efficiency and economical standpoint. The reciprocation of the live electrodes 25 provides a circulation of treated oil which is mixed with the inflowing emulsion continuously during the operation of the dehydrator. The oil which has dropped through the annular opening 15 is 105 drawn through the openings 19 into the upper end of the tube 17 and is mixed with the emulsion and the treated oil which has been drawn through the openings 52.

From the foregoing description it is apparent that my invention provides a very simple means for mixing treated oil and untreated emulsion together immediately before it passes through the treating space. This is the foremost feature of the invention. 110

I claim as my invention:

1. An electrical dehydrator comprising: a tank; a grounded electrode mounted in said tank; a live electrode supported above said grounded electrode, there being a treating space between said electrodes; means for introducing emulsion into said treating space; a valve carried by said live electrode; means for operating said valve so as to introduce treated oil into said treating space to be mixed 120

- with said emulsion; oil outlet means for said tank; and water outlet means for said tank.
2. An electrical dehydrator comprising: a tank; a grounded electrode mounted in said tank; a live electrode supported above said 5 grounded electrode, there being a treating space between said electrodes; means for introducing emulsion into said treating space; a valve carried by said live electrode; means for reciprocating said live electrode, thus operating said valve so as to introduce treated oil into said treating space to be mixed with 10 said emulsion; oil outlet means for said tank; and water outlet means for said tank.
3. An electrical dehydrator comprising: a tank; a grounded electrode mounted in said tank; a live electrode supported above said grounded electrode, there being a treating space between said electrodes; a tube extending 15 downward from said grounded electrode, said tube connecting to said treating space; means for introducing emulsion into said tube, said emulsion flowing into said treating space; a valve carried by said live electrode; means for reciprocating said live electrode, thus operating said valve so as to introduce 20 treated oil into said treating space to be mixed with said emulsion; oil outlet means for said tank; and water outlet means for said tank.
4. An electrical dehydrator comprising: a tank; a grounded electrode mounted in said tank; a live electrode supported above said 25 grounded electrode, there being a treating space between said electrodes; a tube extending downward from said grounded electrode, said tube connecting to said treating space; means for introducing emulsion into said tube, said emulsion flowing into said treating 30 space; a valve carried by said live electrode; means for reciprocating said live electrode, thus operating said valve so as to introduce treated oil into said treating space to be mixed with said emulsion; oil outlet means for said tank; and water outlet means for said tank.
5. An electrical dehydrator comprising: a tank; a grounded electrode mounted in said tank, there being a space around said 35 grounded electrode; a live electrode supported above said grounded electrode, there being a treating space between said electrodes; a tube extending downward from said grounded electrode, said tube connecting to said treating space; means for introducing emulsion into said tube, said emulsion flowing into said treating 40 space; a valve carried by said live electrode; means for reciprocating said live electrode, thus operating said valve so as to introduce treated oil into said treating space to be mixed with said emulsion; oil outlet means for said tank; and water outlet means for said tank.
6. An electrical dehydrator comprising: a tank; a grounded electrode mounted in said tank, there being a space around said grounded electrode; a live electrode supported above said 45 grounded electrode, there being a treating space between said electrodes; a tube extending downward from said grounded electrode, said tube connecting to said treating space, there being an opening formed at the upper end of said tube through which treated oil which has fallen through said space around said space around said grounded electrode may pass into said treating space; means for introducing emulsion into said tube, said emulsion flowing into said treating space; a valve carried by said live electrode; means for reciprocating said live electrode, thus operating said valve so as to introduce treated oil into said treating space to be mixed with said emulsion; oil outlet means for said tank; and water outlet means for said tank.
7. In a dehydrator, the combination of: a pair of spaced electrodes providing a treating space therebetween; means for introducing an emulsion into said treating space; and valve means in one of said electrodes for admitting treated oil directly into said treating space.
8. In a dehydrator, the combination of: a pair of spaced electrodes providing a treating space therebetween; means for introducing an emulsion into said treating space; and valve means operated by a deciprocation of one of said electrodes for admitting treated oil into said treating space.
9. In a dehydrator, the combination of: a pair of spaced electrodes providing a treating space therebetween; means for introducing an emulsion into said treating space; and check valve means in one of said electrodes for admitting treated oil into said treating space but preventing any reverse flow.
10. In a dehydrator, the combination of: a pair of spaced electrodes providing a treating space therebetween; means communicating between said treating space and a body of treated oil; and fluid-operated valve means in said last-mentioned means for admitting treated oil into said treating space.
- In testimony whereof, I have hereunto set my hand at Los Angeles, California, this 30th day of July, 1926.
- HAROLD C. EDDY.
